CLAIM

The ornamental design for a duct tap with an indented end, as shown and described.

DESCRIPTION

FIG. 1 is a front right perspective view of a first embodiment of the duct tap with an indented end; the front left perspective view being a mirror image of FIG. 1;

FIG. 2 is a front elevational view of the duct tap of FIG. 1; FIG. 3 is a front right perspective view of a second embodiment of the duct tap with an indented end; the front left perspective view being a mirror image of FIG. 3; and, FIG. 4 is a front elevational view of the duct tap of FIG. 3. The broken lines shown in FIGS. 1 and 3 are for illustrative purposes only and form no part of the claimed design.
